WIREBOUND BOX BLANK

Arthur F. Durand, Ravinia, Ill., assignor to
 Saranac Patents Holding Company, Benton
 Harbor, Mich., a Corporation of Michigan

Application December 5, 1930. Serial No. 500,164

6 Claims. (Cl. 217—12)

This invention relates to cleat construction for wirebound or similar boxes.

Generally stated, one object of the invention is to provide a novel and improved formation of the cleats of the box or crate or other container, whereby the tongue of the cleat is, in effect, tapered toward its end, either a straight taper or a curved taper, longitudinally of the cleat, while the notch or groove of the other end of the cleat is, in effect, tapered transversely of the cleat, either by a straight taper or a curved taper, whereby certain interlocking action and elements of strength are obtained, in the engagement of the cleats with each other, when the ends of the cleats interlock, thereby to form a box or crate of the desired form or shape.

Another object is to provide a novel and improved relative formation of the cleats, whereby the notch or groove at one end of the cleat is provided with three walls, whereby the tongue of another cleat does not extend entirely through the thickness of the cleat having said notch or groove, the end of the tongue being covered or concealed by the third or end wall of the notch in the other cleat.

To the foregoing and other useful ends, the invention consists in matters hereinafter set forth and claimed and shown in the accompanying drawings, in which—

Fig. 1 is a bottom plan view of a wirebound box blank having the cleats thereof formed in accordance with the principles of the invention;

Fig. 2 is an enlarged end view of the box or crate in finished condition;

Fig. 3 is an enlarged bottom plan view of one of the cleats of said blank;

Fig. 4 is a side elevation of said cleat;

Figs. 5, 6, 7, 8 and 9 are respective views of cleats, showing different forms of the invention.

As thus illustrated, referring to Figs. 1 to 5, inclusive, the invention comprises a wirebound box blank comprising four sheets or side wall sections 1, 2, 3 and 4, having reinforcing cleats 5 on the under side thereof. Each cleat has its one end provided with a tapered tongue 6, a straight taper, longitudinally, of the cleat, while the other end of the cleat is provided with a groove or notch 7 which is tapered transversely of the cleat. In this way, when the two cleats are substantially at right angles to each other, the tapered tongue of one cleat will move straight ahead into the flaring or tapered notch or groove of the other cleat, when the blank is folded into

box form. In this way, a cleat tongue, which is tapered toward its end, moves easily and smoothly into a notch having a flaring mouth on the under side of the cleat, so that folding of the blank is facilitated, as less accuracy is required in the manipulation and positioning of the cleat ends relatively to each other, preliminary to their engagement with each other.

As shown in Fig. 6, the cleat formation is substantially like that previously described, but in this case the tongue 8 is rounded at its end, the other sides of the tongue being parallel, and the notch 9 is correspondingly formed, whereby this notch or groove has three side walls; but, even in this case, the tongue 9 is, in effect, tapered toward its end by a rounding taper, and the notch or groove is correspondingly tapered or formed to receive the tongue.

In Fig. 7, the construction is similar to that shown in Fig. 5, but in this case the end of the straight tapered tongue 10 is rounded, and the notch or groove 11 in the other cleat is similarly formed, whereby a notch or groove, which is tapered transversely of one cleat, providing a flaring mouth at the bottom of the cleat, receives a tongue tapered longitudinally of another cleat; but in this case also, the notch 11 has three side walls.

In Fig. 8, the construction is similar to that shown in Figs. 6 and 7, but in this case the tongue 12 is rounded in the form of a half circle, and the notch or groove 13 of the other cleat is similarly formed, whereby a tongue which, in effect, is tapered longitudinally of one cleat, is received in a groove or notch which is tapered transversely of another cleat; and in this case, the notch 13 has three side walls, but the bottom wall of the notch is much thicker than the two lateral side walls.

In Fig. 9, the tongue 14 of one cleat is tapered transversely of this cleat, while the similarly formed groove or notch 15 is tapered longitudinally of the other cleat; but, as will be seen, it is true that in this case the notch or groove 15 has three side walls, the two lateral side walls, and the transverse walls, which is at the top of the cleat. Thus, in Figs. 6, 7, 8 and 9, the end of the tongue of one cleat extends to, and is concealed by, an end wall or side wall of a notch in the other cleat, which provides a strong and non-splitting formation for the ends of the cleats. In Fig. 5, it will be seen that splitting is less liable than with certain formations heretofore employed for the cleats, as in this case the tongue 6 is thicker at its base than at its end, and the two prongs at

each side of the notch 7 are thicker at the top of this cleat than at the bottom thereof, thus insuring ease of folding, as well as strength and less liability of splitting.

5 The tongues 6, 8, 10 and 12 are, in effect, tapered tongues, and their respective notches are, in effect, tapered notches. Also, the entrance to each notch, in all forms of the invention, is at the bottom of the cleat, while the other end of 10 the notch or groove is at or adjacent the top surface of the cleat, to which top surface the said sheets 1, 2, 3 and 4 are secured. In addition, it will be understood that the binding wires 16 are secured to the sheets and the cleats by staples (not 15 shown) in the usual and well known manner. With the formation shown in Figs. 6, 7, 8 and 9, the sheets do not overlie any notches or grooves, inasmuch as in each of these forms of the invention, the notch has a top wall engaging the under 20 side of the sheet of veneer or other material. It will be understood that the cleats are preferably made of wood, although any suitable material can be employed. But when wood is employed, the 25 formation employed for the ends of the cleats is of value and advantage, in the way of strength and non-splitting tendencies, as heretofore explained.

The notches of Figs. 6 to 9 inclusive have a 30 covering wall at the top, and each notch is thus open only at the bottom and end thereof. In Figs. 5 to 8 inclusive the tongue is thicker at its base than the extreme end thereof when viewed from the top, but is of uniform width when viewed 35 from the side, and of the same area at top and bottom.

What I claim as my invention is:

1. A reinforcing wood cleat for boxes or crates, 40 formed to strengthen the corners of the box, having the grain of the wood extending lengthwise thereof, characterized by the fact that said cleat has a tongue at one end and a notch at the other end thereof, said tongue being in effect tapered toward its end, longitudinally of the grain of the 45

cleat, whereby the tongue is thicker at its base than at the extreme end thereof, when viewed from above, but is of uniform width when viewed from the side, and has the same area at the top and bottom thereof, said notch being in effect 80 tapered transversely of the cleat, from the bottom of the cleat toward the top thereof, crosswise of the grain, whereby a plurality of cleats of this formation will interlock at their ends, at the corners of the box, thereby to reduce the danger of splitting of the cleats when the box is dropped or roughly handled.

2. A structure as specified in claim 1, said notch having a side wall at the top of the cleat, formed 85 integral with the two lateral walls thereof.

3. A structure as specified in claim 1, said notch having flat opposing sides which extend clear through from one side of the cleat to the other, and said tongue having flat opposite sides co-extensive with the opposing sides of the notch, 95 the end of said tongue being flat.

4. A structure as specified in claim 1, said notch having a rounded end, and said tongue having a rounded end fitting the rounded end of the notch.

5. A structure as specified in claim 1, said tongue having opposite sides which are parallel for a distance, and said notch having sides which are parallel for a similar distance.

6. A reinforcing wood cleat for boxes or crates, 100 formed to strengthen the corners of the box, having the grain of the wood extending lengthwise thereof, characterized by the fact that said cleat has a tongue at one end and a notch at the other end, said notch having a covering wall at the 105 top of the cleat between the two lateral walls of the cleat, leaving only the bottom and end of the notch open, whereby a plurality of cleats of this formation will interlock at their ends, with each tongue end against a notch-covering wall, at the 110 corners of the box, thereby to reduce the danger of splitting of the cleats when the box is dropped or roughly handled.
